UNITED STATES PATENT OFFICE.

CHARLES J. BOE, OF PITTSBURGH, PENNSYLVANIA.

ASH RECEIVER.

Application filed February 24, 1925. Serial No. 11,035.

This invention relates to ash receivers for the use of smokers but more particularly to tops for the same, and has for its primary object to provide a simple and useful article 5 of this class.

A further object of my invention is to provide a top which may be used on a variety of different kinds of receptacles and will form therewith an ash tray. The many other objects and advantages of my invention will be better understood by reference to the following specification when considered in connection with the accompanying drawing illustrating a selected embodiment thereof, 15 in which:—

Fig. 1 is a plan view of my improved ash tray top, illustrating one method of use.

Fig. 2 is a vertical section on the line 2—2 of Fig. 1, and

20 Fig. 3 is a vertical section illustrating a different method of use.

Referring to the drawing, my improved ash tray top comprises a substantially cup-shaped member 5 having a rim 6 and opening 7 preferably centrally located therein.

The body of the ash receiver top is preferably made of wire netting as 8 having a mesh sufficiently large to permit the ashes to fall therethrough when a burning cigar 30 or cigarette is placed thereon but of insufficient size to permit the passage of such cigar or cigarette. The ends of the wires forming the netting are preferably welded, soldered, or otherwise attached to the inner face of 35 the rim 6 as at 9.

The opening to admit the cigar or cigarette butts to the receptacle as 10 may be formed in various ways but I prefer to cut away the necessary portion of the netting 40 and insert a sheet metal band as 11 which may be attached to the netting in the same manner as the band 6 forming the rim. The portion of the netting surrounding this band 10 may be depressed as at 12 so that 45 when cigars or cigarettes are placed thereon they will tend to slide toward the middle of the top, but it should be clearly understood that this portion may be made flat, if preferred. When the depressed form of top 50 is used, it is advisable to have the band 11 project above the adjoining portion of the netting, so that the cigars or cigarettes will not accidentally pass through the opening 7 into the receptacle. It will be readily appreciated that the body of my improved top

may be made of perforated metal instead of netting.

The ash receptacle top forming the present invention is adapted to be used in a variety of different ways. In Figs. 1 and 2 the top is shown applied to an ordinary can such as is used to contain cigarettes. These tops may be sold separately and will convert any type of can or receptacle into a very convenient form of ash tray. This top may be slid over a receptacle in the manner illustrated in Figs. 1 and 2 or placed in such a receptacle as illustrated in Fig. 3. In Fig. 3 the ash receiver top is placed in a shallow receptacle as 13 and rests on its bottom edge. 70

An ordinary saucer or shallow dish may be used as the receptacle, as will be readily evident. The cup shaped form of the top causes the cigar supporting surface to be maintained at an interval from the bottom 75 of the receptacle.

In the ash receptacle top shown in Figs. 1 and 2, I have incorporated a deflector as 14, which in the present embodiment consists of a metal strip or wire bent in substantially 80 U-shape and having its ends 15 attached to the sheet metal band 11 surrounding the opening to receive the cigar or cigarette butts. The primary object of this deflector is to prevent the accumulation of these butts 85 directly beneath the opening. It will be readily appreciated that this deflector may be made in many different ways. This deflector may be made in different lengths, depending upon the depth of the vessel on 90 which the top is to be used, or it may be adjustable for different depths, as will be readily appreciated.

It will be evident from the foregoing description that my device will permit substantially any form of receptacle to be converted into an ash receiver. The top is simple in construction and may be economically produced. This top is very convenient in use as it enables the burning cigar or 95 cigarette to be laid upon any portion of the reticulated supporting surface and any ashes becoming detached therefrom will immediately fall into the receptacle. Such a device is far more convenient than the usual form of ash tray in which small convex plates are provided to permit the smoker to place his cigar or cigarette thereon. Such plates retain the ashes and these ashes frequently 100 adhere to the moistened portion of the cigar 110

or cigarette unless the smoker is always careful to place the same on a clean portion of the plate or to remove such ashes as have been previously deposited thereon.

5 I am aware that the form and arrangement of parts may be considerably changed without departing from the spirit of my invention, and I reserve the right to make all such changes as fairly fall within the
10 scope of the following claims.

I claim as my invention:

1. In combination with an ash receiver having a top provided with an aperture for the passage of ashes, cigar butts or the like,
15 a deflector comprising a member having a comparatively narrow edge disposed substantially centrally beneath said aperture.

2. In combination with an ash receiver having a top provided with an aperture for the passage of ashes, cigar butts or the like,²⁰ a deflector suspended from said top and disposed substantially centrally beneath said aperture.

3. In a top for an ash receiver having a substantially cup-shaped member having a portion thereof reticulated, an opening in said body to admit objects of greater size than can pass through the reticulated portion thereof, a metal band surrounding said opening and attached to said body, the combination of a deflector suspended from said band.²⁵
